S. Couillard, Jr.

Wool Cleaner

Patented Mar. 30, 1833.

Fig. 1.

Fig. 2.

1780

Samuel Couthard Junr: of Boston
State of Massachusetts.

Letters Patent.

The schedule referred to in these Letters Patent and making part of the same containing a description in the words of the said Samuel Couthard for himself of his improvement in the machine for cleaning wool and detaching or separating hairs &c therefrom

To all persons to whom these presents shall come Be it known that I Samuel Couthard Junr: of the City of Boston in the County of Suffolk and Commonwealth of Massachusetts a mechanician have invented and applied to one a new and useful improvement in the art of cleaning animal's wool or such like substance, and detaching and separating hairs from the hairs and other foreign materials contained and mingled with said wool, or such like substance in their place or otherwise by extending & straightening the fibers of said wool or such like substance in such a manner as to bring the hairs and foreign materials wholly or principally into the surface of said wool or such like substance thus extending and straightening and then removing said hairs and foreign materials by rapping cutting, pinching, blowing, or striking them off, etc in medicinal contrivance and arrangement with the application and mode of operating the hand for the accomplishment of the purpose or purpose aforesaid as known before in that the principle of my said invention and the means whereby I accomplish the objects aforesaid by the machinery and apparatus

with the ends of glazing the same, may be descended
& left full, in general terms as follows to wit;

First by causing the wool or such like substance
to pass or be drawn from a feeding slot, instead for the
same, like and between two or more great ribbed or plain
rollers, properly fixed & arranged, for the purpose in order
that said wool, or such like substance may be presented
on the side aforesaid rollers so fixed & arranged oppo-
site to that where it enters between them, to a brother
cylinder hereinafter described, in an uniform, regular, and
gradual manner & thus be better prepared for subsequent
operations.

Second by causing said wool or such like substance
to pass or be drawn over & upon or against a rotating
ribbed or brother cylinder or cylinders, roller or rollers,
hand or handy between or against the same or any
such like cylinder or cylinder roller or rollers, handy
handy, said or these in such number & with such
properly fixed & arranged for the purpose so that said
wool or such like substance while in the process of
passing or being drawn or extended is extended
elongated, or drawn into a much thinner thread or
fiber, and the fibers of said wool or such like
substance in a degree straightened and laid parallel
to each other while the same and foreign materials
or particles are commingled with the said wool or such
like substance are beaten and presented on the surface
or surface of said wool or such like substance, which
will be by this operation in a measure beaten, combed
and cleared out from said wool and other foreign mat-
terials, as well as from dust & dirt.

Third, by passing said wool or such like sub-
stance to pass or be drawn from such cylinder or cylin-

roller, or rollers, bare or hairy, as above mentioned or
as, when between or against two or more drawing
rollers, rolled, flared, or plain properly connected with
a band bold or upon, & fixed and arranged for the
purpose, so that said wool or such like substance while
in the process of passing or being drawn as aforesaid
by the comparative velocity in the revolution of said
drawing rollers may receive a greater degree of elonga-
tion & be presented in a thinner sheet or layer and
the fibres of said wool or such like substance be still
more straightened, and said, more parallel with each
other, & at the same time the aforesaid sheet or
layer of said wool or such like substance shall
in during the process of passing or being drawn as
aforesaid this & between the said drawing roller
be arranged as aforesaid, drawn, pinched or tightly
held connected over or upon of said drawing rollers,
and the ends of the fibres of the same arranged in con-
sequence of the comparative velocity of the revolution
between this middle, later or pinched, of said drawing
rollers & that the hairs or other foreign materials
connected, and commingled with said wool or such
like substance, are loosened and presented on the surface
or surface of the same in such a manner as to be
easily detached & taken wholly off by scraping
cutting, pinching, drawing or sticking or otherwise
operating on or against them while the wool or such
like substance thus tightly held is in the process of
passing or being drawn this among, over or upon the
said drawing roller or rollers & the bold or upon con-
nected place & arranged as aforesaid.

Method for drawing said wool or such like
substance when of any kind or pinched & in the process

1822-2

of passing or being drawn as above described to be
pore and clean of burrs and other foreign materials
by the means of any scraper, passocet, picker, beater,
or blower, one or more which shall move against or other-
wise act upon or against said burrs or other foreign
materials so that said wool or such like substances
may pass as be drawn in a sheet or layer on to a re-
cining cylinder suitably fixed and arranged for the
purpose or be otherwise taken away in a disentangled
and cleaned state & in a good condition for the subsequent
operations of the manufacturer.

And also I have herein declared that I
have applied my said invention to use yet this decla-
ration is not to be taken to mean public use, but merely
that use which is necessary for experiments and trial
without which my said invention could not have
been proceeded with complete use.

These may be considered to be the general
principle of my invention relative to the art of
cleaning animal wool & such like substances
of detaching and separating therefrom brass and other
foreign materials connected and mingled with the
same in the fleece or otherwise & of delivering said
wool & such like substances in a clean and light
improved state . But the nature of my
said invention & the manner in which the purposes
aforesaid are accomplished with the mechanical con-
trivances used therefor . & the modes in which the
machinery & the parts thereof are arranged & applied
& made to operate in order to clean and free the wool
or such like substance in the condition above mentioned
may perhaps be better understood by reference to the
plan & drawing hereto annexed marked A, B, C, D, E, F,

which may be broken and considered as a part of this my specification
 A, on this plan represents a strong quadrangular frame made
 (wood or any other suitable material) of sufficient length and width to
 receive at the same time a whole flock of wool of such quantity as on
 instances may require, B, is a feeding cloth on which the wool or such
 its substance to be operated upon is placed; it is made of coarse or
 other suitable material for the purpose and passes around an end
 roller C. & around the lower of the two feeding rollers D, E,

E. Are two feeding rollers of about one inch and half diameter,
 but may be varied in size according to the state of the wool or the
 said substance - I make use of only two feeding roller - but more
 may be used if thought necessary. The uppermost of these two rollers
 is ribbed or flattened, in order that burrs & foreign materials in the
 wool may not be too much broken & flattened down by passing
 between them & also with a view the better to retain and hold
 back the wool, and convey it more gradually to the teethed cylinder D.

D. Is a cylinder about six inches diameter round with teeth
 which project from its surface from thence to four eighths of an inch
 these teeth are from one sixteenth to one eighth of an inch in diameter
 cutted and bent downward in the manner of the letter S. & slot in
 the cylinder about one foot of an inch apart. Both the form, size,
 and position of the cylinder as well as of the teeth with which it
 is armed may be varied according to the quality and condition
 of the wool to be operated upon. This cylinder is
 used on the side of the feeding roller B, E, opposite to that
 where the wool comes between them and so near them that the
 teeth of the same may take the wool as near the first or last of
 the rollers B, E, as possible. J. J. J. I. S. are drawing rollers
 or a combination or combination of drawing rollers (as shown in
 fig. 3,) connected with a band belt or upon E, extending the
 whole length of them. The rollers J. J. J. are of the same size
 nearly as one of which is flattened and none of them may be so, if drawn
 sufficient. These three drawing rollers J. J. J. are fixed and

1130

and are then introduced as are in their usual manner of
rolling. But the drawing rollers 1.2. are of a similar size and
unprovided of their grooves except by the belt or apron 3. By
the belt, or upon the rollers 1.2. are above kept in their proper position
and made to revolve in whirling by the elasticity of the belt or apron
3. they are allowed to revolve more or less so as to admit the passage
of bars or other materials of greater or less size.

The drawing rollers 3.3.3. as seen in fig. 3. are about
one inch and a half in diameter & the small drawing rollers 1.2. about
one half inch in diameter & arranged as there represented, but the size
of the same may be varied as well as the arrangement & number in
same degree, and still effect the same purpose.

It is an intermediate shaft connected with suitable pinions
hubbs and gearings for driving the machinery.

E. Is an endless belt or apron made of canvas or some other
suitable material, and passing around a large roller, etc. and also
and covering the combination of drawing rollers 3.3.3. & 1.2.

F. Is called the preventer made of iron, steel or other material suitable
for the purpose. It is in the form of a thin plate or leaf
to be placed that one edge of the same is parallel to the surface
of the outward small drawing roller 2. & in contact with the belt
or apron 3. which passes over the roller 2. The preventer is from one
to two inches in width extending the length of the rollers & from
one side will be one eighth of an inch in thickness but may be
varied in its dimensions as may be convenient in the use of the
preventer. It is in contact with the belt or apron 3. is filed or worn
down to a blunt edge while the other edge or back is firmly fixed by
screws or otherwise to a strong piece of iron steel or other suitable
material which gives it firmness and stability.

This preventer F. may be placed stationary in the position
in which it is intended to operate or it may be so fixed that
it can be readily thrown back as seen in fig. 4.

G. Is the beater or clapper it may be made of wood iron or

any material suitable for the purpose. It is a cylinder with projections or wings the outward edges of which are filed or toothed transversely with the axis of the cylinder and making alternately different angles with the same, ... This beater or clipper is so placed that the projections or wings as it revolves may come in contact with the bars and other foreign material as near the blunt edge of the peculiar g, as possibly can. It may be made square or in other forms or otherwise contrived to effect the same purpose.

I. is a piece of iron or other suitable substance, near the bottom of which the belt or upon roller A. runs in its axis ... at the upper end of I. there is a screw and nut suited for shortening or lengthening the same, the lower end being movable up and down,) and then the belt or upon I. is loosened or tight.

M., represents the guides or regulators of the belt or upon, I.

A. is a large roller for the belt or upon I.

C. is a large cylinder for the purpose of receiving the wool, or such like substance from the belt or upon I., in a clean state in the form of a sheet; this layer or otherwise roll'd around the same.

E. is a pulley around which a band passes and connects it with another pulley G. on the shaft of the beater or clipper B., which it serves to drive. G. is the pulley to the shaft of the beater or clipper H., ... R. is the pulley around which the band S. passes connecting it with another pulley on the shaft H., which with suitable gearing is the main drive of the machinery ...

The foregoing is a description of the mechanical contrivances and machinery which I make use of in my contrivances I. for accomplishing the purpose herein before mentioned all of which with the application and arrangement of the same may be further illustrated and better understood by a brief account of the mode of operation as following to wit,

The wool or such like substance in the form or otherwise with the bars or other foreign materials connected and weighed with the same is placed upon the frame abut, 13, from this it

down on it when between the feeding roller T & T' in a general
direction of the fiber by the teeth of the roller T being exposed,
the teeth of roller T', being much larger than the feeding
roller T, it causes as it were the fibers of the cloth with
which it is covered with a velocity four or five times as great as that
produced by the feeding roller T. The consequence is that the
wool or such other substance being retained or held back by the
feeding roller T, is drawn out into a sheet or layer four or five
times as thin as that produced by the feeding roller T', at the
same time the fibers are straightened and arranged more parallel
to each other, the burrs and other foreign materials, are loosened
without being wounded and mixed up with the wool and in a
considerable degree presented on the surface & the cost of it
of other such like substances by this operation is in a degree
combed and cleared out from such marks & bushes without loss
of fibers broken;

The next operation of the wool takes place on the side of the foot-hill *explosion* D , opposite to that where the bulk of the snow takes in doing the wool from the feeding valley E nearly on a level with them,

Here the belt is upon E passing against and below the drawing rollers $g, g, g, 1, 2$, receiving the wool from the toothed cylinder D , and as the drawing rollers $g, g, g, 1, 2$, are made to revolve with greater rapidity than the cylinder D , the consequence is that, the wool is elongated into a still finer sheet or layer and the fibers retained parallel to each other and undisturbed more so. Besides by the arrangement of the drawing rollers $g, g, g, 1, 2$, the two smaller ones $1, 2$ being left empty at their extremities except by the belt as upon E , which allows them by its elasticity to exert no more or less wear to the rollers g, g, g than to the $1, 2$ and the smaller number of rollers g, g, g are more likely to last longer than the larger number of rollers 1, 2 and 3 and 4 and 5 and 6 and 7 and 8 and 9 and 10 and 11 and 12 and 13 and 14 and 15 and 16 and 17 and 18 and 19 and 20 and 21 and 22 and 23 and 24 and 25 and 26 and 27 and 28 and 29 and 30 and 31 and 32 and 33 and 34 and 35 and 36 and 37 and 38 and 39 and 40 and 41 and 42 and 43 and 44 and 45 and 46 and 47 and 48 and 49 and 50 and 51 and 52 and 53 and 54 and 55 and 56 and 57 and 58 and 59 and 60 and 61 and 62 and 63 and 64 and 65 and 66 and 67 and 68 and 69 and 70 and 71 and 72 and 73 and 74 and 75 and 76 and 77 and 78 and 79 and 80 and 81 and 82 and 83 and 84 and 85 and 86 and 87 and 88 and 89 and 90 and 91 and 92 and 93 and 94 and 95 and 96 and 97 and 98 and 99 and 100 and 101 and 102 and 103 and 104 and 105 and 106 and 107 and 108 and 109 and 110 and 111 and 112 and 113 and 114 and 115 and 116 and 117 and 118 and 119 and 120 and 121 and 122 and 123 and 124 and 125 and 126 and 127 and 128 and 129 and 130 and 131 and 132 and 133 and 134 and 135 and 136 and 137 and 138 and 139 and 140 and 141 and 142 and 143 and 144 and 145 and 146 and 147 and 148 and 149 and 150 and 151 and 152 and 153 and 154 and 155 and 156 and 157 and 158 and 159 and 160 and 161 and 162 and 163 and 164 and 165 and 166 and 167 and 168 and 169 and 170 and 171 and 172 and 173 and 174 and 175 and 176 and 177 and 178 and 179 and 180 and 181 and 182 and 183 and 184 and 185 and 186 and 187 and 188 and 189 and 190 and 191 and 192 and 193 and 194 and 195 and 196 and 197 and 198 and 199 and 200 and 201 and 202 and 203 and 204 and 205 and 206 and 207 and 208 and 209 and 210 and 211 and 212 and 213 and 214 and 215 and 216 and 217 and 218 and 219 and 220 and 221 and 222 and 223 and 224 and 225 and 226 and 227 and 228 and 229 and 230 and 231 and 232 and 233 and 234 and 235 and 236 and 237 and 238 and 239 and 240 and 241 and 242 and 243 and 244 and 245 and 246 and 247 and 248 and 249 and 250 and 251 and 252 and 253 and 254 and 255 and 256 and 257 and 258 and 259 and 260 and 261 and 262 and 263 and 264 and 265 and 266 and 267 and 268 and 269 and 270 and 271 and 272 and 273 and 274 and 275 and 276 and 277 and 278 and 279 and 280 and 281 and 282 and 283 and 284 and 285 and 286 and 287 and 288 and 289 and 290 and 291 and 292 and 293 and 294 and 295 and 296 and 297 and 298 and 299 and 300 and 301 and 302 and 303 and 304 and 305 and 306 and 307 and 308 and 309 and 310 and 311 and 312 and 313 and 314 and 315 and 316 and 317 and 318 and 319 and 320 and 321 and 322 and 323 and 324 and 325 and 326 and 327 and 328 and 329 and 330 and 331 and 332 and 333 and 334 and 335 and 336 and 337 and 338 and 339 and 340 and 341 and 342 and 343 and 344 and 345 and 346 and 347 and 348 and 349 and 350 and 351 and 352 and 353 and 354 and 355 and 356 and 357 and 358 and 359 and 360 and 361 and 362 and 363 and 364 and 365 and 366 and 367 and 368 and 369 and 370 and 371 and 372 and 373 and 374 and 375 and 376 and 377 and 378 and 379 and 380 and 381 and 382 and 383 and 384 and 385 and 386 and 387 and 388 and 389 and 390 and 391 and 392 and 393 and 394 and 395 and 396 and 397 and 398 and 399 and 400 and 401 and 402 and 403 and 404 and 405 and 406 and 407 and 408 and 409 and 410 and 411 and 412 and 413 and 414 and 415 and 416 and 417 and 418 and 419 and 420 and 421 and 422 and 423 and 424 and 425 and 426 and 427 and 428 and 429 and 430 and 431 and 432 and 433 and 434 and 435 and 436 and 437 and 438 and 439 and 440 and 441 and 442 and 443 and 444 and 445 and 446 and 447 and 448 and 449 and 450 and 451 and 452 and 453 and 454 and 455 and 456 and 457 and 458 and 459 and 460 and 461 and 462 and 463 and 464 and 465 and 466 and 467 and 468 and 469 and 470 and 471 and 472 and 473 and 474 and 475 and 476 and 477 and 478 and 479 and 480 and 481 and 482 and 483 and 484 and 485 and 486 and 487 and 488 and 489 and 490 and 491 and 492 and 493 and 494 and 495 and 496 and 497 and 498 and 499 and 500 and 501 and 502 and 503 and 504 and 505 and 506 and 507 and 508 and 509 and 510 and 511 and 512 and 513 and 514 and 515 and 516 and 517 and 518 and 519 and 520 and 521 and 522 and 523 and 524 and 525 and 526 and 527 and 528 and 529 and 530 and 531 and 532 and 533 and 534 and 535 and 536 and 537 and 538 and 539 and 540 and 541 and 542 and 543 and 544 and 545 and 546 and 547 and 548 and 549 and 550 and 551 and 552 and 553 and 554 and 555 and 556 and 557 and 558 and 559 and 560 and 561 and 562 and 563 and 564 and 565 and 566 and 567 and 568 and 569 and 570 and 571 and 572 and 573 and 574 and 575 and 576 and 577 and 578 and 579 and 580 and 581 and 582 and 583 and 584 and 585 and 586 and 587 and 588 and 589 and 590 and 591 and 592 and 593 and 594 and 595 and 596 and 597 and 598 and 599 and 600 and 601 and 602 and 603 and 604 and 605 and 606 and 607 and 608 and 609 and 610 and 611 and 612 and 613 and 614 and 615 and 616 and 617 and 618 and 619 and 620 and 621 and 622 and 623 and 624 and 625 and 626 and 627 and 628 and 629 and 630 and 631 and 632 and 633 and 634 and 635 and 636 and 637 and 638 and 639 and 640 and 641 and 642 and 643 and 644 and 645 and 646 and 647 and 648 and 649 and 650 and 651 and 652 and 653 and 654 and 655 and 656 and 657 and 658 and 659 and 660 and 661 and 662 and 663 and 664 and 665 and 666 and 667 and 668 and 669 and 670 and 671 and 672 and 673 and 674 and 675 and 676 and 677 and 678 and 679 and 680 and 681 and 682 and 683 and 684 and 685 and 686 and 687 and 688 and 689 and 690 and 691 and 692 and 693 and 694 and 695 and 696 and 697 and 698 and 699 and 700 and 701 and 702 and 703 and 704 and 705 and 706 and 707 and 708 and 709 and 710 and 711 and 712 and 713 and 714 and 715 and 716 and 717 and 718 and 719 and 720 and 721 and 722 and 723 and 724 and 725 and 726 and 727 and 728 and 729 and 730 and 731 and 732 and 733 and 734 and 735 and 736 and 737 and 738 and 739 and 740 and 741 and 742 and 743 and 744 and 745 and 746 and 747 and 748 and 749 and 750 and 751 and 752 and 753 and 754 and 755 and 756 and 757 and 758 and 759 and 760 and</u

and as aforesaid are brought wholly or principally on the surface in a loosened state so as to be taken off, while they are allowed by the elasticity of the bolt or upon it to pass without being materially broken by the outward small drawing roller 2.

The wool or such like substance being now drawn into a thin sheet or layer the fibers straightened and laid parallel to each other, and the wool lightly held around the outward drawing roller 2, with the burs and foreign materials passed wholly or principally on the surface in a loosened state the next operation is to remove them from the wool,

This is done by the preventer 3 & the beater or clipper 4, the blunt edge of the preventer 3, pressing firmly on the wool tightly held, on the small drawing roller 2, raises the burs & foreign materials as the wool is passing so under it & while the beater 4, revolving with great rapidity comes in contact with & operates upon the burs & foreign materials, as they are raised by the preventer 3 & thus takes them all over the blunt edge of the same... And the wool being now effectively cleaned and freed from burs and foreign materials passing into the cylinder 5 or may be taken off by hand or otherwise.

I claim sundry of the above described parts of the machinery and modes of operating which to some extent are far different purposed than those herein mentioned may have been done, and lastly as well as machinery and modes of operating which are advantageous to my said invention, but which may be considered various at the discretion of the operator or mechanician and which a skillful mechanician readily understand... I hereby particularly & explicitly declare that what is hereby claimed by me as my invention in the art of cleaning animal wool or such like substance is the attaching & separating therefrom the burs and other foreign materials contained and mingled with said wool and such like substance in the form or character by straightening and straightening the fibers of said wool so such like substance in such a manner as to

15561

bring the hair and foreign materials wholly "pennipally" or
the surface of said wool or such like substances, then extending
a straight line, and then removing said hairs & foreign materials
by scraping, cutting, paring, planing, or striking them off as herein
before described.

I also hereby claim the mechanical contrivances and arrangement
thereof, with the modes of applying and operating the same, for
the accomplishment of the purpose or purpose aforesaid as specific
and more particularly as herein after mentioned, to wit the arrange-
ment and adaptation of the two small drawing rollers marked in
the plan and drawing hereto annexed marked a, b,) 1:2, in the
combination of drawing rollers, figg. 1, 2, which are the same
& suggestion of said Sawyer of said Boston aforesaid &
used in my said invention, by said Sawyer as concert with
the testimony that the foregoing is a true spec-
ification of said invention in the art of cleaning a animal
wool or such like substances & the mechanical contrivances &
arrangement thereof with the modes of applying & operating
the same, as herein described. I have hereunto set my hand
this 2nd day of March in the year of our Lord 1833.

Witness,

John Knapp
George Stewart
